UNITED STATES PATENT OFFICE.

JOSEPH DERK, OF PHILADELPHIA, PENNSYLVANIA.

DESIGN FOR A TEXTILE FABRIC.

Application filed July 10, 1926. Serial No. 18,300. Term of patent 3½ years.

To all whom it may concern:

Be it known that I, JOSEPH DERK, a citizen of the United States, residing in the city and county of Philadelphia, State of Pennsylvania, have invented a new, original, and ornamental Design for a Textile Fabric, of which the following is a specification, reference being had to the accompanying drawing, forming part thereof.

The drawing illustrates approximately one-half of the textile fabric, and the design is repeated at the opposite end thereof.

The figure is a plan view of a textile fabric showing my new design.

I claim:—

The ornamental design for a textile fabric, as shown.

JOSEPH DERK.
